METHOD OF MANUFACTURING INTEGRAL FINNED TUBING

Edward Penner, Detroit, Mich., assignor, by mesne assignments, to Calumet and Hecla Consolidated Copper Company, Calumet, Mich., a corporation of Michigan

Application April 15, 1940, Serial No. 329,819

5 Claims. (Cl. 29—157.3)

The invention relates to integral finned tubing of that type in which the metal forming the fins is displaced axially and radially from the outer portion of the tube blank. This operation is usually performed by placing the tube blank on a mandrel and feeding it axially with respect to the fin-forming means, such for instance as longitudinal series of rolls circumferentially spaced about the blank. Thus, the fins will be formed throughout the entire length of the blank and because of the displacement of the metal, the wall thickness intermediate the fins is necessarily reduced. Such tubing may be used in the manufacture of heat exchange units where the ends of the fin tubes are connected into headers so as to form a sealed joint. This necessitates stripping the fins from the end portions of the tube, leaving a wall thickness which is reduced from that of the original blank. It has been found that the wall thickness required for making a proper joint with the header is greater than that which is sufficient for the finned portion of the tube, but where the fins are formed as above described, the wall thickness must necessarily be the same throughout the length of the tube. Thus, the weight of metal in the tubes must be considerably increased if the end portions are to be made of greater thickness.

It is the object of the instant invention to obtain a method of forming integral finned tubes which will have greater wall thickness in certain portions of their length than in other portions. More particularly, it is an object to increase the wall thickness of the unfinned portions of the tubes over that of the finned portions thereof. With these objects in view, the invention consists in the method and in the product as hereinafter set forth.

In the drawing:

Figure 1 is a longitudinal section partly in elevation, illustrating the manner of finning the tube;

Figure 2 is an enlarged section after the completion of the finning operation;

Figure 3 is a longitudinal section, illustrating the manner of removing the mandrel and expanding the contracted tube portions;

Figure 4 is a similar enlarged view of a further expansion operation;

Figure 5 is a diagrammatic cross section illustrating the manner of finishing the outer surface of the tube ends;

Figure 6 is a view similar to Figure 2, showing a modified construction;

Figure 7 is an elevation, illustrating one construction of finned tube unit having an unfinned return-bent portion.

In manufacturing the finned tubes by my improved method the tube blanks A, preferably formed of seamless drawn tubing of copper or

similar material, are first placed upon a mandrel B which has one or more portions thereof reduced in diameter. Thus, as shown in Figure 1, the central portion B' of the mandrel fits the internal diameter of the tube A, while the end portions B² and B³ are somewhat smaller in diameter. C are the rolls between which the tube is axially fed, said rolls being suitably fashioned to progressively displace the metal in the outer portion of the cross section of the tube, so as to form radially projecting helical fins A'. The radial inward pressure of the rolls upon the outer surface of the tube is resisted by the portion B' of the mandrel, so as to preclude any contraction in diameter of this portion. On the other hand, the portions of the tube which extend over the portions B² and B³ of the mandrel are not so supported, and as a consequence these portions will be contracted in diameter by the pressure of the rolls, instead of having fins formed thereon. If desired, the tube may be contracted over the small diameter portions of the mandrel in advance of the feeding of the same into engagement with the rolls, and this is preferably done on the forward end of the tube which first comes in contact with the rolls. Thus, as shown in Figure 1, the forward portion A² has been contracted by means of dies (not shown) to fit the mandrel portion B³. A tapering pilot D is then engaged with the forward end of the mandrel, preferably by means of a threaded shank D' engaging a correspondingly threaded aperture. This pilot is of a diameter to just clear the rolls, the portion A² of the tube being slightly larger. Thus, when the tube is fed between the rolls the latter will merely slightly indent the outer surface of the portion A², but the following portion A³ which is over the mandrel portion B' will have the fins A' formed thereon. The rear end portion A⁴ of the tube which is over the mandrel portion B², will be contracted by the pressure of the rolls to conform to the mandrel with only a slight indenting of its outer surface. Thus, as shown in Figure 2, the central portion of the tube is finned while the opposite end portions are without fins and contracted in diameter. In performing the operations just described the tube may be slightly elongated so that its rear end will project beyond the end of the mandrel, as shown at A⁵. This portion is then cut off, after which the pilot D is removed and the mandrel is driven out by a suitable tool, such as E. This tool will expand the contracted portion A², while the axial movement of the mandrel will expand the portion A⁴ by the mandrel portion B', as shown in Figure 3. The mandrel may then be completely removed, after which the end portions of the tube may, if desired, be further expanded by a suitable tool, such as F shown in Figure 4. Finally, these end portions are externally finished

to remove the indentations therefrom, this operation being performed by any suitable tool, such as diagrammatically shown in Figure 5, having a pilot G fitting within the tube and one or more external cutters H. This will not only smooth the outer surface but will also remove any slight eccentricity between the outer and inner surfaces, so as to form an annular wall of uniform thickness.

For certain uses it may be desirable to form a tube having one or more unfinned portions intermediate finned portions thereof. This may be accomplished by the use of a mandrel, as shown in Figure 6, in which portions I fitting the internal diameter of the tube are connected by a portion J which is of smaller diameter. The tube and mandrel are then fed between the fin-forming rolls, as previously described, which will merely contract the portion K which is over the mandrel portion J, while forming fins on the portions K' and K² at opposite ends of the portion K. The portion K will thus be of greater wall thickness than the portions K' and K² with only a slightly indented outer surface. When the mandrel is driven out of the tube, this portion K will be enlarged to its original diameter and its outer surface may then be finished to remove the indentations. Such a construction is useful in the forming of return-bent finned tubes, as illustrated at L in Figure 7.

A finned tube of the construction above described when formed from seamless drawn copper tubing, will have a high rate of heat exchange, due to the thermal conductivity of the material and the integral fins. At the same time, the unfinned portions may be of any desired wall thickness without the necessity of increasing the wall thickness of the finned portions.

When, as shown in Fig. 4, the unfinned portion of the tube is finally expanded to a diameter greater than that of the original tubular blank, the thickness of the walls will be correspondingly reduced. However, this thickness may be maintained to be at least as great as that of the finned portion, thereby avoiding any weakened portion.

What I claim as my invention is:

1. The method of forming integral finned tubing having one or more unfinned portions of greater wall thickness comprising, placing a tubular blank upon a mandrel having portions thereof fitting and supporting the wall of the tube, and one or more other portions of smaller diameter spaced from the tube wall, feeding the blank and mandrel as a unit axially and throughout their length in intersecting relation to external fin-developing means which exerts radially inward pressure in excess of the resistance of said tubing, whereby fins will be developed and the wall thickness intermediate the same reduced in the portion of the tube supported by the mandrel while the portions unsupported by the mandrel will be radially contracted to avoid substantial fin development, removing the mandrel from the tube, and expanding the contracted portions thereof.

2. The method of forming integral finned tubing having an unfinned end portion of greater wall thickness comprising, placing a tubular blank upon a mandrel for fitting and supporting the wall of the tube but having an end portion of smaller diameter, feeding said tube and mandrel together as a unit axially throughout their length in intersecting relation to external fin-developing means which exerts radially inward pressure

in excess of the resistance of said tubing, whereby fins will be developed and the intermediate wall thickness reduced in the portion of said tube supported by the mandrel while the end portion will be radially contracted without substantial fin development, removing the mandrel from the tube, expanding the unfinned end portion thereof, and externally finishing said end portion concentric with the inner surface thereof.

10. 3. In a method of forming integral finned tubing having one or more finned portions of exactly predetermined length intermediate unfinned portions, the steps of placing the tubular blank on a mandrel having a portion corresponding in length to each portion of the tube to be finned, said portion being of a diameter to fit within and support the wall of the tubular blank, said mandrel also having portions of smaller diameter forming shoulders at opposite ends of each larger portion, and feeding the blank and mandrel as a unit axially in intersecting relation to external fin developing means which exerts radially inward pressure in excess of the resistance of said tubular blank, whereby said blank will be radially contracted about said shoulders in the unsupported portions thereof and appreciable fins will be developed only on the supported portion between said shoulders.

4. In a method of forming integral finned tubing having one or more finned portions of exactly predetermined length intermediate unfinned portions, the steps of placing the tubular blank on a mandrel having a portion corresponding in length to each portion of the tube to be finned, said portion being of a diameter to fit within and support the wall of the tubular blank, said mandrel also having portions of smaller diameter forming shoulders at opposite ends of each larger portion, contracting the leading end of the blank over the smaller diameter of the corresponding end of the mandrel, and feeding the blank and mandrel as a unit axially in intersecting relation to external fin developing means which exerts radially inward pressure in excess of the resistance of said tubular blank, whereby said blank will be radially contracted about said shoulders in the unsupported portions thereof and fins of appreciable height will be developed only on the supported portion between said shoulders.

5. In a method of forming integral finned tubing having one or more finned portions of exactly predetermined length intermediate unfinned portions, the steps of placing the tubular blank on a mandrel having a portion corresponding in length to each portion of the tube to be finned, said portion being of a diameter to fit within and support the wall of the tubular blank, said mandrel also having portions of smaller diameter forming shoulders at opposite ends of each larger portion, contracting the leading end of the blank over the smaller diameter of the corresponding end of the mandrel, securing said blank on said mandrel by means abutting the leading end of the blank, and feeding the blank and mandrel as a unit axially in intersecting relation to external fin developing means which exerts radially inward pressure in excess of the resistance of said tubular blank, whereby said blank will be radially contracted about said shoulders in the unsupported portions thereof and fins of appreciable height will be developed only on the supported portion between said shoulders.
